UNITED STATES PATENT OFFICE

EDWIN H. SCHEELE, OF NEW YORK, N. Y., ASSIGNOR TO WESTFIELD RIVER PAPER COMPANY, INC., OF RUSSELL, MASSACHUSETTS, A CORPORATION OF MASSACHUSETTS

DESIGN FOR EMBOSSED GLASSINE PAPER

Application filed July 10, 1930. Serial No. 36,317. Term of patent 14 years.

To all whom it may concern:

Be it known that I, EDWIN H. SCHEELE, a citizen of the United States, residing at New York, in the county of New York and State of New York, have invented a new, original, and ornamental Design for Embossed Glassine Paper, of which the following is a specification, reference being had to the accompanying drawing, forming part thereof.

The figure is a plan view of a section of embossed glassine paper showing within dotted lines a complete unit of my new design which is to be repeated over any desired area.

I claim:

The ornamental design for embossed glassine paper as shown and described.

EDWIN H. SCHEELE.
